UNITED STATES PATENT OFFICE.

MARTIN R. KENYON, OF PROVIDENCE, RHODE ISLAND.

IMPROVEMENT IN LAMPS.

Specification forming part of Letters Patent No. 42,492, dated April 26, 1864.

To all whom it may concern:

Be it known that I, MARTIN R. KENYON, of Providence, in the county of Providence and State of Rhode Island, have invented a new and Improved Lamp-Chimney Attachment; and I do hereby declare that the following is a full, clear, and exact description of the same, reference being had to the annexed drawings, making part of this specification, in which—

Figure 1 is a plan of a lamp-top having my improved chimney attachment. Fig. 2 is a perspective view of the same. Fig. 3 is a vertical section.

Like parts in all the figures are marked by similar letters of reference.

My improvement has particular reference to a certain improved construction of a lamp-top set forth in Letters Patent of the United States No. 36,680, granted to Albert Taplin, October 14, 1862, the distinctive features of which are, first, that the cone and chimney-holder are connected to the lamp-cap by a hinge, and, secondly, that the chimney is secured to the said chimney-holder and cone, which are formed in one piece, by means of a spring in lieu of a screw, as formerly used. Now, the security of the chimney depends wholly on the efficiency of the said spring, and in practice it is found that the spring employed by the said Taplin, as described in his specification, is quite insufficient for the security of the glass chimney, owing to the fact that it is made of a flat piece of metal and of necessity in a form that deprives it of a greater portion of its elasticity, and to the fact that, besides performing the office of holding the chimney in its place, it is used as a thumb-piece or lifter in removing the chimney with its chimney-holder and cone to trim and light the lamp, in consequence of which the said spring soon becomes permanently bent or broken and entirely useless for the purpose.

My improvement is intended to obviate this difficulty; and to this end it consists in the formation of a thumb-piece or lifter projecting from the chimney-holder and distinct and separate from the spring, which it relieves of all strain and injury arising from the lifting and closing of the hinged cone and chimney-holder in trimming or lighting the lamp; and my improvement further consists in a pecu-

liar construction of the spring and its arrangement with the cone and chimney-holder, whereby the spring is rendered more elastic and secure for the purpose intended.

That others skilled in the art may be enabled to make and use my improvement, I will proceed to describe the same.

In the drawings, A is the cone *a a*; the chimney-holder, and B is the lamp-cap, the two pieces being connected by the hinge C. Upon the opposite side of the chimney-holder from the hinge I form the thumb-piece or lifter S, which may be of the same piece of metal with the chimney-holder, which it lifts and closes down when desired independently of the spring. The spring *t*, I form of wire bent into the requisite form, as shown, to confine the chimney to the holder *a*, in connection with the projections *i i* thereon, and formed with a coil or coils, *e e*, suitably and compactly arranged to give the loose end of the said spring increased elasticity, and thereby render it more secure for holding the chimney. This spring is soldered in holes punched in the sides of the cone and chimney-holder in a firm and substantial manner.

Besides the advantages above mentioned, this spring can be made with a considerable saving in both material and labor, and it proves in practice to be a more durable and effective spring for the purpose than the one heretofore used in this connection.

I am aware that a flat or sheet-metal spring has heretofore been used for securing the glass lamp-chimney to the lamp-top in a number of ways, as shown and described in Letters Patent to E. F. Jones, and to O. and H. S. Snow, and in the rejected application of J. W. Taber, of March 23, 1861; also, that a helical spring acting directly upon a rod has been used to secure the chimney to the lamp-top, and I would not therefore be understood as claiming, broadly, the use of a spring arranged in either of the ways above referred to for the purpose specified.

I am also aware that the use of a coiled wire spring, in combination with the upper part of a lamp-top, when constructed, attached, and fitted to produce the effect substantially as therein described, has been secured by Letters Patent to Oliver Snow, dated April 8, 1862, and I therefore wish it understood that I do not claim, broadly, the use of a coiled

spring for the purpose specified. Neither do I claim the particular construction or mode of attaching and fitting a coiled spring to a lamp-top to produce the effect described and set forth in said Letters Patent, my improvement being confined to the peculiar construction and arrangement of the two-coil spring *t*, when the same is combined with the thumb-piece or lifter *S* in the manner and for the purpose herein set forth: Furthermore, I do not claim the said lifter *S* separately, nor except it be combined and arranged with the said two coiled spring *t* and in such a manner that each, the said spring *t* and the said lifter *S*, is auxiliary to the other, and operate and are used in connection with advantage and assistance to each, substantially as herein

contemplated and therefore shown, a similar lifter being shown without a spring in Letters Patent ordered to L. J. Atwood on his application filed January 6, 1863.

Having thus defined the nature and extent of my improvement, what I claim, and desire to secure by Letters Patent, is—

The combination of the aforesaid hinged cone and chimney-holder, the thumb-piece or lifter *S*, and the two-coil spring *t*, when the whole are constructed, arranged, and used for the purpose and effect herein described and set forth.

MARTIN R. KENYON.
